FLASHING STRIP

Alonzo W. Bailey, Cleveland, Ohio

Application June 19, 1941, Serial No. 398,782

5 Claims. (Cl. 72—126)

This invention relates broadly to building structures and more specifically to flashing for sealing the seams between basement floors and foundation walls or footings.

In buildings constructed with concrete basement floors it is customary irrespective the type of material employed in the foundation wall or footings, to cast the floor slab after the foundation has been set. This practice invariably produces a seam or crack at the junction of the floor with the wall and permits the seepage of water or the presence of moisture in the basement through capillary attraction.

Various expedients, such as agricultural drain tile, waterproof surface coatings and caulking have been employed, from time to time, in an effort to eliminate this difficulty but none of these expedients have been found satisfactory either in point of durability or efficiency.

The invention contemplated herein comprises generally a series of flanged strips or plates inset in the foundation wall and floor grouting in such a manner as to span the seam between floor and wall or footing and thus arrest the passage of moisture therethrough.

A further object of the invention resides in the provision of an expansion joint or yieldable fold in the flashing strips in the zone of the seam to accommodate such movement of the footings as occur when the building settles and further to facilitate flexure of the strip, compensative of dimensional inaccuracies in the building structure.

Other objects and advantages more or less ancillary to the foregoing and the manner in which all the various objects are realized will appear in the following description, which considered in connection with the accompanying drawing, sets forth the preferred embodiment of the invention.

Referring to the drawing which is illustrative of the preferred embodiment of the invention:

Fig. 1 is a vertical section through a foundation wall, footing and basement floor illustrating the improved flashing plate in use;

Fig. 2 is a vertical sectional view through a foundation wall and footing showing certain of the concrete wall forms in place and the flashing strip supported thereby;

Fig. 3 is a similar sectional view of a foundation wall and footing illustrating the position of the flashing strip after the concrete forms have been removed;

Fig. 4 is a view in perspective of the improved flashing strip; and

Fig. 5 is a vertical section through an interior

wall and floor construction illustrating an application of the flashing in such environs.

As illustrated, the improved flashing 10 comprises a strip of metal formed with marginal flanges 11 and 12 and a plurality of lineal folds 13 extending throughout the medial axis thereof. In use the strips are partially embedded in the masonry forming the foundation wall or footing and partially embedded in the grouting of the concrete floor, the strips being arranged in end to end relation with each other and soldered to form a continuous band around the periphery of the floor slab. In the concrete wall structure illustrated in Fig. 2 the flashing strip is supported by timbers or wooden blocks 14 and 15 constituting a portion of the concrete form, the strip being arranged with the crest of the fold 13 in the parting line or seam 16 between the wall 17 and the floor slab 18. The blocks 14 and 15 in the concrete form may be of rectangular transverse section, as illustrated or may be constructed with angular edge portions (not shown) to accommodate the support of the flashing strip in the position illustrated in Fig. 3. In either event one or more of the folds 13 should be disposed within the seam between the foundation wall and floor slab in order to facilitate independent movement thereof such as occurs when the building settles without rupture of the metallic strip.

The flange 11 and the portion of the flashing within the wall 17 is preferably turned upwardly when assembled in the form to assure the intimate engagement of the concrete with the strip during the erection of the wall. The flange 12 and portion of the flashing within the floor is preferably turned downwardly during assembly of the form in order to restrain the flow of concrete and produce a void or air cell 19 beneath the strip when the floor is cast. As illustrated in Fig. 5, the improved flashing may be employed to seal the seam between a floor slab and a partition wall or stair well having a subterranean footing. In such environs the flashing strip is arranged as heretofore described though a second flashing strip 10 may be inset in the opposed face of the same wall to seal the joint between the wall and the floor in the second room.

The flashing 10 is preferably formed of sheet copper strips formed of appropriate length to facilitate the ready handling thereof during the erection of the building and while in transi-
tus. Obviously, other rust resisting materials possess-
ing sufficient resiliency to flex under the move-
ment of the foundation wall as it settles may be
used with equal faculty in substitution for cop-

per. The ends of the flashing strips are preferably overlapped and soldered as the strips are set or the wall is cast thereabout though effective results may be obtained by uniting the ends of contiguous strips with the conventional folded tinner's joint.

In a concrete wall the flashing is assembled in the forms with a portion thereof extended into the interior mold, whereupon the wall and footings are poured or cast. Subsequently the forms are removed, leaving a portion of the flashing strip extending from the face of the wall into the interior of the room or basement. The protruding portion of the flashing is disposed in a plane defining substantially the mid thickness of the floor so that the strip will be fully submerged in the concrete when the floor slab is cast.

It will be understood that the improved flashing may be used in conjunction with tile, brick or other forms of masonry and that the invention is not restricted, in application, to the concrete foundation walls shown in the accompanying drawing. It will be further understood that the invention comprehends the application of the flashing to arrest the flow of water downwardly as in a wall and roof structures or wall and floor which is above the grade line.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. In a building structure embodying a foundation wall and basement floor defining a seam at the juncture of the floor with the wall, flashing therefor to preclude the passage of moisture therethrough comprising a continuous strip of metal embedded in the wall and floor and ar-

ranged to span the seam and a fold in said strip in which at least one of the legs of the metal forming the fold is disposed in its entirety within the seam to facilitate independent movement of the wall in relation to the floor.

5. In a building embodying a foundation wall and a concrete floor constructed with a seam at the junction of the floor with the wall, flashing therefor comprising a strip of copper, flanges 10 along the longitudinal edges thereof, a V fold within the medial axis thereof, said strip being embedded in the wall and floor with at least one of the legs of the V fold disposed in said seam.

3. Flashing to preclude the passage of water 15 through the joint between a foundation wall and a basement floor, comprising a flexible rust resisting metallic strip, flanges along the side edges thereof to facilitate anchorage of the strip in the wall and floor respectively, a plurality of folds 20 along the media axis of the strip, one of the folds defining a sharp angle and a straight vertical wall disposed within the joint between the wall and the floor to facilitate independent movement of the wall and the floor without rupture 25 of the strip.

4. In a building structure embodying a concrete wall and a concrete floor cast with a seam at the junction thereof, flashing for sealing said seam comprising a strip of metal embedded in the wall and floor to span the seam, a plurality 30 of folds in said strip constituting a double walled lineal rib, the metal forming one of the walls of said rib being disposed in said seam.

5. In a building structure embodying a concrete wall and a concrete floor cast with a seam at the junction thereof, flashing for sealing said seam comprising a strip of metal embedded in the wall and floor to span the seam, a V fold in 35 said strip disposed in said seam, with the open end of the V in said seam, whereby said V fold may flex without rupture upon separation of the floor and wall.

ALONZO W. BAILEY.
